UNITED STATES PATENT OFFICE.

FRANK C. ANDERSON, OF CINCINNATI, OHIO.

SWITCH-STAND.

1,389,730.

Specification of Letters Patent. Patented Sept. 6, 1921.

Application filed March 3, 1921. Serial No. 449,401.

To all whom it may concern:

Be it known that I, FRANK C. ANDERSON, a citizen of the United States, residing at Cincinnati, in the county of Hamilton and 5 State of Ohio, have invented certain new and useful Improvements in Switch-Stands, of which the following is a specification.

My invention relates to ground-lever parallel-throw switch-stands in general, and 10 more particularly to the kind disclosed and claimed in my Patent No. 1,360,862, dated November 30, 1920, upon which the present invention is an improvement. Its object, like the switch-stand of that patent, is to 15 combine ease of manual switch-throwing operation with control of the point-rails by a weighted handle, to permit normal operation without excessive vibration or opening of the point-rails, but to permit opening if 20 the switch is run through, without resilient or breakable connections. A further object is to adjust the stand to different switches and to compensate for wear, as in the patent referred to. It is the especial object of the 25 present invention to simplify and facilitate the construction and operation of my switch-stand in those respects. Other objects, peculiar to the present invention, as well as in common with those of the just mentioned 30 patent, will appear in the course of the ensuing description.

I attain these objects by the device illustrated, for example, in the accompanying drawing, in which—

35 Figure 1 is a sectional plan view of the switch-stand, the section being on a plane corresponding to the line 1—1 of Fig. 2;

Fig. 2 is a sectional front elevation, the section being on a plane corresponding to 40 the line 2—2 of Fig. 1;

Fig. 3 is a vertical front-to-rear section on a plane corresponding to the line 3—3 of Fig. 1;

Fig. 4 is a perspective detail view of the 45 rack;

Fig. 5 is a partial bottom plan view of the base and the switch-throwing crank mounted therein;

Fig. 6 is a vertical lengthwise section of 50 the adjustable crank, on a plane corresponding to the line 6—6 of Fig. 1; and

Fig. 7 is a perspective detail view of one of the shims.

The base of the stand comprises the middle part 1 with curved juncture-parts 2 at opposite ends curving down to the foot-

plates 3 similar to those disclosed and claimed in said patent. Also, as in that patent, this base comprises the front shaft bearing 4 and the segmental extension 5 at 60 the rear, with the crank-and-clutch bearing opening 6 down through the middle part 1 substantially concentric with said rear extension, and, between this opening 6 and the front bearing 4, the substantially semi-cylindrical depression 7. It likewise has the two front pedestals 8 at the opposite sides of the depression 7, and the rear pedestal 9, running entirely across between the rear end of the depression 7 and said bearing 65 opening 6. The casing is also similar to that of the patent referred to, with front shaft bearing 10, rear extension with the target-shaft-bearing opening 11, flat top, and open bottom, permitting it to be placed 70 down over the interior working parts after the latter have been fully assembled on the base, and to be bolted to the base by means of the front bolts 12 and the rear bolts 13, as in said patent. This casing, and the 75 base and several details thereof, are claimed in said patent, but are fully disclosed herein to elucidate the disclosure of the present invention.

The handle-lever 14 has at one end the 80 weight-handle 15 of approved design, and at its other end, preferably forged integrally therewith, the pinion shaft 16. This shaft 16 lies in the front shaft bearings 4 and 10 of the base and casing, respectively, and 85 has keyed on it the pinion-segment 17 occupying the depression 7 of the base and having at its front end a short hub 18, through which hub is a pin 19, passing through the shaft 16. As here disclosed, this pinion-segment 17 has seven teeth, the terminal ones 90 of the series being diametrically opposite; and it is so keyed to the shaft 16 that its middle tooth is alined with the handle lever 14. This pinion and lever arrangement is 95 similar to that in said patent, the most notable difference being that there are seven teeth in the pinion instead of five; the pinion being larger in proportion to the other parts of the stand than in said patent. 100 These are only details of size, to afford a greater degree of movement.

The rack 20 comprises the flat body 21 with six teeth 22 in longitudinal series along the bottom of the body 21, and with the 110 cylindrical upward extension or pin 23 substantially midway of the length of the body

21 on the top thereof, and preferably slightly nearer to the rear edge than to the front edge of said body. The rack teeth 22 are shorter than the front-to-rear width of the body, leaving longitudinal bearing surfaces 24 and 25 at front and rear, to bear on the tops of the pedestals 8 and 9, respectively. These pedestals are of the proper height to support the rack for correct meshing with 10 the teeth of the pinion-segment 17, and for the rack 20 to travel transversely of the casing on these pedestals as the segment 17 is turned through a half revolution by throwing the handle-lever 14 from one side 15 of the stand to the other. The rack 20, at its extreme positions, is supported by the rear pedestal 9 and by one of the front pedestals 8; and to act as guides under these conditions the rack has small lugs 26 at 20 the corners of the body 21, and small lugs 27 about midway of the length of the body 21, at front and rear, bearing against the adjacent sides of the pedestals, so that one or the other pair of corner lugs 26 and the 25 middle lugs 27 serve to hold the rack in alignment with the pedestals in either one of its two extreme positions.

30 The target-shaft 28 will be understood to be of suitable design in its upper part, with target elements and lamp-supporting means, for instance as shown in the patent referred to, and similarly it has its lower end threaded and some distance above the threads has a transverse opening. The intermediate 35 crank 29 comprises, in one casting, preferably of malleable iron, the rather large hub 30 down through which the target-shaft 28 fits snugly; and in the front part of the arm of this crank is the short longitudinal 40 slot 31, by which it has an easy fit down over the upward extension or pin 23 of the rack 20 when the crank 29 is thus mounted on the target-shaft 28 with the latter bearing in the casing-top opening 11 and the lower- 45 end part of the hub 30 fitting down in the crank-and-clutch opening 6 of the base. This lower end part of the hub 30 has its lower face transversely grooved, and up a proper distance has the annular flange 32 50 that rests on top of the base around the opening 6, holding the crank 29 at the right height to work easily with the rack 20; while the target-shaft 28 is supported in this crank by a pin 33 slipped through the 55 transverse opening 34 in the hub 30 at the right height, and through the target-shaft opening. These details of crank and target-shaft mounting are such as are disclosed and claimed in said patent, as is also the 60 holding of the pin 33 in its position by its extension out against the inner concave wall of the segmental rear extension of the casing.

65 The direct switch-throwing crank-hub or crank-block is of T-shape, with the stem

of the T cylindrical and extending upward into the bearing opening 6 of the base, where its upper end has a threaded or tapped central opening 36 with clutch teeth 37 at opposite sides (Fig. 6). The lower-end part of 70 the intermediate-crank hub 30 extends only partly through the opening 6, which opening is through a much thickened part of the base middle part 1, and so is of considerable length; and the upper end part of 75 the hub 35 meets the hub 30 therein, with its clutch-teeth 37 fitting in the corresponding transverse grooves 38 in the lower end of the intermediate-crank hub 30 (Fig. 3), in a manner similar to that of the crank 80 connection as disclosed and claimed in the patent referred to, and with the advantages set forth therein.

The transverse lower part of the T-shaped crank hub 35 has an opening through it 85 from end to end, and its opposite ends are flat, except that at their bottom edges they have transverse horizontally extending ledges 39. The direct-switch-throwing crank arm 40 is generally of the shape of a pin or bolt, with one end part 41 threaded and its other end part 42 flattened into the form of an eye; and it also comprises, next to this eye part 42, a flange 43 to bear against one end of the transverse part of the 90 crank-hub when the pin part of this crank arm is inserted through the lengthwise opening in said transverse part. The top of this flange 43 preferably is rounded; but its bottom is made straight to fit snugly down on 100 the transverse ledge 39 of the respective end of the crank-hub part, thus preventing turning of the crank-arm in the hub, and, this straight bottom being parallel with the flat upper and lower sides of the eye part 42, 105 the crank-arm is held in proper switch-connecting position in the hub 35. A number of shims or washers 44 are provided, each of general U-shape (Fig. 7) with the members of the U flat transversely; these 110 being like those shown and claimed in my patent referred to, and being assembled with the crank parts in a similar manner, as claimed therein. In the present invention, however, it is the ledge 39 of the respective 115 adjacent end of the crank-hub part that receives the lower ends of the inverted U-shaped shims or washers 44 as these are placed astraddle of the crank-arm 40 between said end of the hub part and the nut 120 45 screwed onto the threaded end part 41 of the arm 40. Thus the shims or washers 44 are prevented from turning around on the arm 40, so that they cannot escape therefrom sidewise.

125 The connecting-rod 46 is forked, with its members 47 straddling the eye part 42 of the crank-arm 40 and receiving the crank-pin 48 down through the members of the rod and through this eye, in a well known 130

manner. The base middle part 1 has a rear extension 49 having its bottom continuous with the bottom of the thickened part of the base that has the opening 6; this extension 49 being such that the crank-pin 48 never rides from under it at its most rearward position (Fig. 1). The thickening of the base part 1 is also preferably continued forwardly and laterally, as at 50 (Fig. 5), so 10 that there is an extended lower surface, inclusive of that of the extension 49, only slightly above the top of the head of the crank-pin 48, throughout the extent of swinging of the crank-pin under the switch- 15 stand base. In the extension 49, however, at opposite sides of the rear casing extension, are transversely elongated openings or slots 51, through which the crank-pin 48 may be dropped into its position when 20 making the switch connection; the elongation of these slots 51 permitting this whatever the length to which the switch-throwing crank is adjusted, as is permitted by transferring one or more of the shims or 25 washers 44 from one end of the transverse crank-hub part to the other while the nut 45 is loosened, then tightening this nut. As the crank-pin 48 passes quickly under the slot 51, it is practically prevented from 30 rising out of its position at all times; and as it is always out from under the slot 51 when the switch is thrown to either position, with the pin 48 under the stand or out under the extension 49, rise of the pin under 35 the switch-holding strains and vibrations is positively prevented. By this the use of cotters, nuts and the like to hold the pin, with their liability of breakage or displacement, is obviated.

40 The assembly of the stand is accomplished as described in the patent referred to; the improved intermediate crank, with its slotted arm fitting over the rack lug or pin 23, being readily placed in position by movement 45 thereof down onto the rack at right angles to the flat top thereof, after the manner of assemblage of the intermediate crank with the other parts, as claimed in my patent referred to. This slotted arm and pin connection 50 between the segment and the intermediate crank permit of a very ample degree of movement of the rack with a given angle of turning of the intermediate crank and switch-throwing crank, coaxially connected 55 as set forth. This allows a very considerable leverage from handle-lever to switch, by virtue of the increased length of the intermediate crank over that of the direct-switch-throwing crank, without adding to the 60 length of the handle-lever or decreasing the length of the direct-throwing crank, neither of which is permissible in practice. This, in connection with the smallness of the pinion permitted, all of which is set forth fully in 65 said patent, allows such leverage as may be needed; on the one hand to permit easy throwing of the switch by the operative holding to the handle of the stand, and on the other hand, enabling the moderate weight of the handle to afford the right resistance to 70 the switch-point movement under traffic to avoid opening under normal conditions, but to permit opening of the point rails when the switch is run through in the wrong direction, without breakage of the switch or stand 75 parts, but with the weighted handle-lever merely being thrown over under the strain imposed by the rolling stock under these abnormal conditions. Thus latches are not needed, except where the switch must be 80 locked, as on main lines.

These advantages, fully set forth in the patent referred to, are realized by the present invention with greater facility, because the slotted-arm and pin connection permits 85 a freer choice of dimensions for these parts than does the connection as disclosed in said patent, in which connections of this manner of assemblage are claimed broadly. Similarly, the novel shim-retaining ledges 39, and the crank-pin retaining parts 49 and 50, facilitate the assemblage of the stand and its switch connection, and add to the safety of railway traffic by their security against 90 disconnection of the parts. It will be understood that the crank-arm 40 is subject to reversal of position in the crank-hub, for a switch of different direction; upon which the opposite one of the two pin-admitting slots 51 would be needed for making the switch 95 100 connection.

It will be understood that this present invention is subject to modifications such as alluded to in the patent referred to, and in such respects as it is equivalent to or identical with the device therein disclosed and claimed, it is subject to the protection of said patent. Therefore, while many details thereof are herein disclosed, and the details hereof are rather specifically shown and described herein, I do not wish to be understood as being limited to such precise showing and description, but having thus fully 105 described my invention, what I claim as new herein and desire to secure by Letters Patent is:

1. In a switch-stand, mechanism comprising a lever and a spur pinion coaxially connected, a rack above and meshing with said pinion and having an upward extension on 110 its top, an intermediate crank above said top of said rack, having a longitudinal slot receiving said upward extension, a crank-block coaxially connected with said intermediate crank, a base forming bearing and 115 supporting means for said mechanism and having an opening through which said intermediate crank and said crank-block are connected, a crank-arm extending through said crank-block, having one end threaded 120

125

130

and having rod-connecting means at its opposite end, a nut on said threaded end, a U-shaped shim inverted and astraddle of said crank-arm between said nut and said 5 crank-block, a projection on said crank-block engaging with the lower edge of said shim, a switch-connecting rod, a crank-pin in connecting position in said connecting-rod and said crank-arm rod-connecting means, a rearward 10 projection on said base, having openings to admit said crank-pin to said connecting position in different positions of said crank-arm, and having a downward projection on its bottom, said rearward and downward 15 projections overlying said crank-pin and preventing its displacement from said connecting position.

2. In a switch-stand, supporting means, a rack element and a lever operatively mounted 20 on said means, a spur pinion coaxially connected to said lever and meshing with the teeth of said rack element, a lever-engaging projection on said rack element, an intermediate crank having a longitudinal slot receiving 25 said projection of said rack element and having a bearing in said supporting means, and a direct switch-throwing crank coaxially connected with said intermediate crank.

3. In a switch-stand, supporting means, a rack element and a lever operatively mounted 30 on said means, a spur pinion coaxially connected to said lever and meshing with the teeth of said rack element, a lever-engaging projection on said rack element, an intermediate crank having a longitudinal slot receiving 35 said projection of said rack element and having a bearing in said supporting means, and a direct switch-throwing crank coaxially connected with said intermediate 40 crank and off-set downwardly therefrom.

4. In a switch-stand, supporting means, mechanism operatively supported by said means, comprising a lever and a spur pinion 45 coaxially connected, a rack element having teeth meshing with said pinion and having a lever-engaging projection, an intermediate crank having a longitudinal slot receiving said projection of said rack element, and a direct switch-throwing crank coaxially connected with said intermediate crank and extending below the lowest part of said supporting means for connection to switch-connecting means therebelow.

5. In a switch-stand, mechanism comprising a lever and a spur pinion coaxially connected, a rack above and meshing with said pinion, an upward projection on the top of said rack, an intermediate crank above said 55 rack and having a longitudinal slot receiving said projection of said rack, a direct switch-throwing crank coaxially connected with said intermediate crank, and means operatively supporting said mechanism.

6. In a switch-stand, a rack element com-

prising a main flat part with teeth and a longitudinal bearing surface along one flat side, and a single crank-engaging projection on its opposite flat side, adapted to enter a crank slot in a crank moved toward said side at right angles to the flat surface of said side.

7. In a switch-stand, a crank-block with opposite flat sides with an opening through it from one flat side to the other, a crank-arm through said opening with retaining means near one end and rod-connecting means at its other end, a shim of general U-shape between said retaining means and said crank-block, astraddle of said crank-arm, and a projection on said crank-block to engage an edge of said shim.

8. In a switch-stand, a crank-block with opposite flat sides with an opening through it from one flat side to the other, a crank-arm through said opening with retaining means near one end and rod-connecting means at its other end, a shim of general U-shape between said retaining means and said crank-block, astraddle of said crank-arm, and projections on said crank-block at its opposite flat sides, to engage an edge of said shim when said shim is placed at either flat side of said crank-block.

9. In a switch-stand, a crank-block having opposite flat sides and an opening through it from one flat side to the other, and projections on said crank-block at its opposite flat sides, for the purpose set forth.

10. In a switch-stand, an intermediate crank having a longitudinal slot for operative engagement with a rectilinearly moving member of said stand, said slot having both ends closed whereby the material of said crank along the sides of said slot is supported at both ends of said slot.

11. In a switch-stand, a base having a bearing for a crank on an upright axis, and having a projection past said bearing to retain connecting means in a crank mounted in said bearing.

12. In a switch-stand, a base having a bearing for a crank on an upright axis, and having projections past said bearing at both sides of said bearing to retain connecting means in a crank mounted in said bearing and swinging to either side of said bearing.

13. In a switch-stand, a base having a bearing for a crank on an upright axis, and having a projection past said bearing to retain connecting means in a crank mounted in said bearing, said projection having an opening near one side of said bearing, to admit the connecting means to the crank at an intermediate position of said crank.

14. In a switch-stand, a base having a bearing for a crank on an upright axis, and having projections past said bearing at both sides of said bearing to retain connecting means in a crank mounted in said bearing.

and swinging to either side of said bearing, said projections having openings at opposite sides of said bearing, to admit the connecting means to the crank at intermediate positions 5 of said crank when swinging to either side of said bearing.

15. In a switch-stand, a base having a bearing for a crank on an upright axis, and having a projection past said bearing to retain 10 connecting means in a crank mounted in said bearing, said projection having an opening prolonged at a substantial angle to the arc of swinging of the crank, to admit the connecting means to the crank at an intermediate 15 position of said crank and at various distances from the bearing axis due to variations in effective length of the crank.

16. In a switch-stand, a base having a bearing for a crank on an upright axis, and having projections past said bearing at opposite 20 sides of said bearing to retain connect-

ing means in a crank mounted in said bearing and swinging to either side of said bearing, said projections having openings prolonged across the arc of swinging of the 25 crank, to admit connecting means to the crank at intermediate positions of said crank when swinging to either side of said bearing and at various distances from the bearing axis due to variations in effective length of 30 the crank.

17. In a switch-stand, a base having a bearing for a crank on an upright axis and having a projection past said bearing out from under said base, and having a downward projection on its bottom contiguous to said bearing, said projections overlying connecting means in a crank mounted in said bearing and preventing displacement of the connecting means from its connecting position. 35 40

FRANK C. ANDERSON.
